UNITED STATES PATENT OFFICE.

GEORGE F. DUNN, OF BROCKTON, MASSACHUSETTS, ASSIGNOR OF ONE-HALF TO THE BROCKTON SUPPLY CO., OF SAME PLACE.

VAMP-FOLDING MACHINE.

SPECIFICATION forming part of Letters Patent No. 651,797, dated June 12, 1900.

Application filed August 12, 1899. Serial No. 727,011. (No model.)

To all whom it may concern:

Be it known that I, GEORGE F. DUNN, of Brockton, in the county of Plymouth and State of Massachusetts, have invented certain new and useful Improvements in Vamp-Folding Machines, of which the following is a specification.

This invention relates to machines for folding vamps of boots and shoes. Owing to the shape of the inner edges of vamps, the same being deeply indented or reentrant, the operation of folding these inner edges has heretofore been almost wholly performed by hand, difficulty having been experienced in designing a machine to properly perform the work. By means of my present invention, however, I provide a practical machine for the purpose of folding the reentrant curved inner edges of vamps or other like articles or pieces of material having reentrant edges.

The invention consists in the novel features of construction and arrangement which I shall now proceed to describe and claim.

Of the accompanying drawings, Figure 1 represents a perspective view, partly broken away, of a vamp-folding machine constructed in accordance with my invention. Fig. 2 represents a top plan view thereof. Fig. 3 represents a side elevation. Fig. 4 represents a longitudinal section. Figs. 5, 6, and 7 represent transverse sectional views, on an enlarged scale, on the line 5 5 of Fig. 5, representing different positions of certain of the operative parts. Figs. 8 and 9 represent sections taken above the folder, showing the parts of the folder in different positions. Fig. 10 represents a detail perspective view, partly broken away and with parts removed, of the former and adjacent portions of the machine. Fig. 11 represents a detail perspective of the fore part of the former. Fig. 12 represents a detail perspective view, partly broken away, of the folder-plates separated. Fig. 13 represents an enlarged detail sectional view on the line 13 13 of Fig. 8. Fig. 14 represents a reverse plan view of a folded vamp.

The same reference characters indicate the same parts in all of the figures.

In the embodiment of my invention shown in the drawings I employ a table upon which the work is supported, a former which is

brought down upon the work and clamps the same to the table, and a folder which is first given a vertical movement transversely across the edge of the former-blade from below the latter and then a lateral or horizontal movement over the top of said blade, whereby the edge of the work is folded around the edge of the blade, and mechanism for withdrawing the former-blade after the fold is made, and holding the work under pressure between the folder and the edge of the work-supporting table. These parts are commonly found in folding-machines of certain well-known types.

The novelty of my invention consists in the peculiar construction of the former and of the folder in order to cause them to operate properly on work having the peculiar reentrant curved edge of a boot or shoe vamp, and in the operating mechanism for said parts, and in certain other details of construction and arrangement.

In the drawings, *a* designates a bed or table provided with suitable supporting-legs *a'* *a'* and planed off flat on top to form a work-supporting table. The middle portion of the table *a* is grooved at *a*² and undercut, and in the groove is fitted a sliding plate *a*³, held in position by a screw *a*⁴. The middle part of this plate *a*³ is cut out and its edge is substantially horseshoe or U shaped, like the inner edge of a vamp, and in practice a number of such plates having their openings of different sizes to correspond to different-sized vamps will be provided and interchangeably fitted to the table.

*a*⁵ is a frame or bracket bolted to the under side of the table *a* and having at its lower end a bearing for a rod *b*. The latter is normally elevated by the tension of a spring *b*² and is connected by a connecting member *b'* with an operating-treadle. At the upper end of the rod *b* above the table *a* is secured a former-carrier *b*³, which supports a two-part former *b*⁴ *b*⁴. The latter consists of rigid frame-pieces, to the under sides of which are attached the former-blades *b*⁵ *b*⁵, whose front ends overlap, as shown in Fig. 11, and provide a continuous inner edge having the form of the inner edge of a vamp. Normally the former is elevated above the work-support-

ing table, as shown in Fig. 3, so that the work can be readily inserted. When the work has been inserted and properly positioned, the former is brought down upon the work by depressing the treadle connected with the rod b , clamping the work to the table. A device is provided for holding the former depressed upon the work, so that the operator can remove his foot from the treadle, said device being best shown in Fig. 4. The rod b near its upper end is provided with a slot b^6 , having an inclined lower edge 2, and a locking key or slide b^7 is provided and fitted to slide into and out of the slot b^6 , the said key having a complementary inclined edge 3. A hand-lever b^8 , fulcrumed at b^9 to the under side of the table a and projecting out to one side thereof, as shown in Figs. 8 and 9, is pivotally attached to the key or slide b^7 by a pin b^{12} and is employed to withdraw said key from the slot b^6 . A spring b^{13} exerts a tension which normally draws the key b^7 into the slot b^6 , and when the rod b and the former are depressed such action will automatically take place, and the key will lock the rod in this depressed position and prevent its return by the action of the spring b^2 . The inclined edges 2 and 3 make a frictional lock, which acts at any point in the descent of the rod b and accommodates the machine to thick or thin vamps. The pivot-pin b^{12} is extended upwardly through a slot c in the lower plate c of the folder-carrier hereinafter described, with which slot the pin has a guiding engagement, serving to guide the movements of the key b^7 .

The frame portions of the former b^4 b^4 are provided with crossed stems or lugs b^{14} b^{14} , which are fitted to slide in diagonally-crossed guiding-grooves in the former-carrier b^8 , as illustrated in Figs. 10 and 2, and said stem portions are connected by links b^{16} b^{16} with a stud b^{17} , screwed into a sliding block b^{18} . The latter is fitted to slide longitudinally in a groove in the rear part of the carrier b^8 and is adapted to be reciprocated by means of a short hand-lever b^{19} , fulcrumed at b^{20} to the top side of the carrier b^8 and formed with a slot which is occupied by the stud b^{17} . A top plate b^{15} , screwed to the carrier b^8 , holds the former-stems b^{14} and block b^{18} in place. It will be seen that the manipulation of the lever b^{17} imparts a reciprocatory movement to the parts of the former b^4 b^4 , which takes place in a forward and outward direction by reason of the diagonal arrangement of the guides, the parts of the former moving diagonally in opposite directions. This movement is utilized in adjusting the former and in removing it from the fold of the work. The overlapping front ends of the former-blades b^5 b^5 are made very thin, and their inner edges make a practically-continuous working edge which can be expanded or contracted by the described reciprocatory diagonal movement of the former parts. The inward or contracting movement of the former is limited by means of a stop-

screw b^{22} , adapted to form an abutment for the sliding block b^{18} to limit the rearward movement of said block, said screw being carried by an upturned ear on the carrier b^8 and locked by a nut b^{23} . The shape and size of the curve formed by the inner edges of the former-blades b^5 b^5 determine that of the vamp, so that for vamps of different sizes the screw-top b^{22} is given different adjustments. I show a gage in the drawings for regulating the adjustment of the former to different-sized vamps, said gage consisting of a pointer b^{21} , attached to the block b^{18} and projecting out through a slot in the top plate b^{15} and a scale on one edge of said slot, over which the end of the pointer passes, as seen in Figs. 1 and 2.

The folder which co-operates with the former in folding the work I have herein shown as composed of two plates c^5 c^5 laid side by side and held between the lower and upper plates c^2 , composing the folder-carrier. Said plates are spaced apart by shouldered studs c^4 c^4 , Fig. 13, and connected by screws c^3 c^3 . On the under side of the lower plate c of the folder-carrier is secured a bracket c^6 , suitably guided between the sides of the frame a^5 and engaged underneath by the forked inner end of a lever c^9 , pivoted at c^{12} to said frame. A treadle (not shown) connected by a connecting member c^{13} to the lever c^9 is employed to oscillate said lever and elevate the bracket c^6 and folder-carrier. The said parts are adapted to be depressed when pressure is removed from the treadle by means of a spring c^7 , interposed between the bracket c^6 and a fixed plate c^8 . The upward movement of the folder-carrier is limited by a stop-screw c^{14} , adapted to abut the under side of the lever c^9 .

The two plates c^5 c^5 composing the folder are provided with oppositely-arranged diagonal slots c^{15} c^{15} , occupied by the vertical studs c^4 c^4 , and are connected by a pair of links c^{16} c^{16} with a pin c^{17} , carried by a lever c^{18} . The latter is fulcrumed at c^{25} to the under side of the table a and projects out to one side thereof, as shown in Figs. 8 and 9. The oscillation of the lever c^{18} by the operator reciprocates the folder-plates c^5 c^5 , the latter moving forward and outward diagonally in opposite directions, as will be seen by comparing Figs. 8 and 9, which show, respectively, the contracted and expanded positions of the folder. The continuity of the front end of the folder is preserved by providing one of the plates c^5 with a pair of thin horizontal plates c^{21} c^{21} , overlapping the other folder-plate c^5 on its upper and lower sides, and providing the latter with a thin vertical plate c^{22} , overlapping the front edge of the first said folder-plate c^5 . The folder-plates are guided with respect to each other by means of sliding dowels or guide-pins c^{19} c^{19} , attached to one of the plates and fitted to slide in holes in the other plate.

c^{23} c^{23} are vertical gage-strips attached to the upper sides of the folder-plates c^5 c^5 , near the outer edges of the latter, and adapted to act as gages to position the inner edges of the

vamp when the latter is first placed on the work-supporting table. The under sides of the folder-plates c^5 c^5 are provided with similar gage-strips c^{24} c^{24} in a corresponding position, which operate, as represented in Fig. 7, to prevent the folded edge of the work from uncurling inwardly.

The machine operates as follows: A vamp, preferably having the front portion of its inner edge snipped in the usual manner, is placed upon the work-supporting table a , when the parts are positioned as represented in Figs. 3 and 4, with the former b^4 b^4 elevated above the table and the folder c^5 c^5 depressed, so that its upper surface is located flush with or slightly below the surface of the table. The inner edges of the vamp are then brought to the gage-strips c^{23} c^{23} , so that said inner edges slightly overlap the folder, and the treadle connected with the rod b is depressed, so as to bring the former b^4 b^4 down upon the vamp, as represented in Fig. 5, so as to clamp the vamp to the table, the former being locked in clamping position by the action of the key b^7 . The treadle connected with the lever c^9 is then depressed, so as to elevate the folder to the level of the former-blades b^5 b^5 . The hand-lever c^{18} is then thrown forward, so as to extend the parts of the folder horizontally over the former-blades, whereby the edge of the vamp is folded around said blades, as seen in Fig. 6. I provide a device whereby the latter part of the throw of the lever c^{18} is utilized in elevating the former slightly, so as to relieve its pressure on the work and permit its ready withdrawal from the fold, said arrangement consisting, as shown, of a lever d , pivoted at d' to the lever b^8 , and having a stop d^2 , adapted to be engaged by the lever c^{18} . As the latter moves forward it engages the stop d^2 and gives a slight throw to the lever b^8 , causing the locking-key b^7 to be slightly withdrawn and permitting the spring b^2 to elevate the former a short distance. The lever b^{19} is then thrown forward to expand the former and withdraw its blades b^5 b^5 from the fold in the work, as shown in Fig. 7, after which the pressure on the treadle controlling the lever c^9 is released and the folder is allowed to descend and hold the fold under pressure between the under side of its plates c^5 c^5 and the work-supporting table. After remaining under pressure a sufficient period of time the foregoing operations are reversed to bring the parts back to their normal positions and the folded vamp is removed and a fresh one subjected to the operation of the machine. The completed vamp v is shown in Fig. 14.

It will be understood that any of the well-known accessories to folding-machines, such as steam heating or other heating devices for applying heat to the machine to set the fold may be employed in connection with my improved vamp-folding machine; but as such accessories form no part of my present invention I have not illustrated the same.

Having thus explained the nature of my in-

vention and described a way of constructing and using the same, though without attempting to set forth all of the forms in which it may be made or all of the modes of its use, what I claim, and desire to secure by Letters Patent, is—

1. In a vamp-folding machine, a former, a curved folder adapted to fold the edge of the work over said former and composed of a plurality of parts or sections, means for expanding and contracting said folder, and means for preserving the continuity of the folder at the junction of its parts, when expanded.

2. In a vamp-folding machine, a former, a curved folder, adapted to fold the edge of the work over the former and composed of a plurality of overlapped parts or sections, and means for expanding and contracting said folder.

3. In a vamp-folding machine, a former, a folder having a U-shaped working edge adapted to fold the edge of the work over the former, and composed of two parts overlapped at their ends, and means for imparting diagonal movements in opposite directions to said parts.

4. In a vamp-folding machine, a folder composed of a plurality of parts having overlapping vertical and horizontal edge portions, and means for expanding and contracting said folder.

5. In a vamp-folding machine, a folder composed of two plates, a carrier therefor, means for reciprocating said plates with respect to the carrier, means for guiding them on the carrier diagonally in opposite directions during their reciprocation, and coacting guiding members on the respective plates controlling the relation of the plates.

6. In a vamp-folding machine, a sectional former, means for moving its parts simultaneously in opposite directions, and a folder adapted to fold the edge of the work over said former.

7. In a vamp-folding machine, a sectional former, means for moving its parts diagonally forward and outward in opposite directions to withdraw them from the fold in the work, and a folder adapted to fold the edge of the work over the former.

8. In a vamp-folding machine, a two-part former, means for simultaneously imparting outward movements in opposite directions to the parts of said former to withdraw it from the fold in the work, and a folder adapted to fold the edge of the work over the former.

9. In a vamp-folding machine, a two-part former, means for imparting diagonal forward and outward movements in opposite directions to the parts of said former to withdraw it from the fold in the work, and a folder adapted to fold the edge of the work over the former.

10. In a vamp-folding machine, a two-part former, a movable carrier therefor, means for simultaneously reciprocating the parts of

the folder with respect to the carrier, oppositely-arranged diagonal guides adapted to direct the reciprocatory movements of said former parts forward and outward in opposite 5 directions to withdraw the former from the fold in the work, and a folder adapted to fold the edge of the work over the former.

11. In a vamp-folding machine, a two-part former, a suitably-guided reciprocatory part 10 and means for moving the same, links connecting the former parts with said reciprocatory part whereby the former parts may be reciprocated, means for guiding the former parts diagonally in opposite directions during their reciprocation, and a folder adapted 15 to fold the edge of the work over the former.

12. In a vamp-folding machine, a two-part former, a movable carrier therefor, a reciprocatory part and means for moving the same 20 mounted on said carrier and connected with the former parts, whereby the latter may be reciprocated, means for guiding said former parts diagonally in opposite directions during their reciprocation, and a folder adapted 25 to fold the edge of the work around the former.

13. In a vamp-folding machine, a curved former composed of a plurality of parts or sections, means for expanding and contracting said former, means for preserving the continuity 30 of the former at the junction of its parts, when expanded, and a folder adapted to fold the edge of the work over the former.

14. In a vamp-folding machine, a U-shaped former composed of two parts overlapped at 35 their ends, means for imparting diagonal movements in opposite directions to said parts, and a folder adapted to fold the edge of the work over the former.

15. In a vamp-folding machine, a curved former composed of a plurality of parts or sections, means for expanding and contracting said former to adjust and operate it, an adjustable stop to regulate the size of the former 40 when contracted, and a folder adapted to fold the edge of the work over the former.

16. In a vamp-folding machine, a curved former composed of a plurality of parts or sections, means for expanding and contracting said former to adjust and operate it, an adjustable stop to regulate the size of the former 45 when contracted, a gage or index to determine the adjustment of said stop, and a folder adapted to fold the edge of the work over the former.

55 17. In a vamp-folding machine, a two-part

U-shaped former, a carrier therefor, oppositely-arranged diagonal guides for guiding the former parts on the carrier, a block mounted to slide on the carrier, and connected with the former parts, means for moving said block, 60 whereby the former parts are reciprocated and the former expanded and contracted, an adjustable stop adapted to abut the said block to limit the contractile movement of the former, a pointer carried by said block and an 65 index arranged on the carrier in proximity to said pointer.

18. In a vamp-folding machine, a work-supporting table, a clamp adapted to descend on said table to clamp the work to the table, a 70 spring or equivalent normally elevating said clamp, means for depressing the clamp, an automatically-acting lock adapted to hold said clamp depressed against the work, said lock having provisions for automatic adjustment 75 to accommodate the clamp to the thickness of the work, and means for retracting said lock to permit the elevation of the clamp.

19. In a vamp-folding machine, a work-supporting table, a former adapted to descend 80 upon the work and clamp the same to the table, a vertical rod supporting said former, and having a locking-abutment, a spring adapted to elevate the rod, a spring-actuated key having a locking-abutment adapted to coöperate 85 with the abutment on the rod to lock the rod automatically when the latter is depressed, thereby holding the former against the work, said locking-abutments being inclined, to accommodate the position of the former to the 90 thickness of the work, and means for retracting said key to release the rod.

20. In a vamp-folding machine, a work-supporting table, a former adapted to descend upon the work and clamp the same to the table, a spring or equivalent normally operating 95 to elevate the former, means for depressing the former, an automatic lock for holding the former depressed upon the work, a folder, means for projecting said folder over 100 the former to fold the work, and mechanism actuated by said means for retracting said lock and releasing the former.

In testimony whereof I have affixed my signature in presence of two witnesses.

GEORGE F. DUNN.
